MACHINE FOR OPERATING ON BLANKS

Arthur L. Currier, New Ipswich, N. H., assignor to Independent Lock Company, Fitchburg, Mass., a corporation of Massachusetts

Application April 6, 1946, Serial No. 660,245

7 Claims. (Cl. 90—21)

1

My present invention is a novel and improved machine designed primarily for grooving key blanks or similar work, and employs a novel method of manufacture.

Heretofore in the manufacture of key blanks of the so-called Yale lock and key type, wherein grooves are formed on opposite sides during the process of manufacturing the same, it has been customary to feed in the blanks by hand with various operations and control of the grooving cutters by manual means, thus limiting the output of the machine to the speed and skill of the operator.

Such blanks have to be cut with great care, being of thin metal; and owing to the extremely slight variations in depth and configuration of the grooves, the keys must be made with great care and accuracy.

In my present machine, I provide entirely automatic means to operate on one or more blanks, simultaneously cutting the obverse grooves on one blank and the reverse on another blank, with capacity for holding a large number of blanks in a magazine or feeder, automatically taking the bottom blank therefrom; forming the desired grooves in the surfaces of the blanks, and automatically re-assembling the blanks thus grooved into another magazine for subsequent operations.

Thus my invention provides a machine which will permit a greatly increased speed of production, and with extreme accuracy, eliminating errors or difficulties incident to any manual operations, and thus enabling one operator to attend a considerable number of machines all in production at the same time, and each operating on a plurality of blanks.

An important feature of my present invention, in addition to the automatic and simultaneous operation on a plurality of blanks, is the construction wherein a removable magazine containing a stack of blanks to be grooved on the obverse side is fitted into the feeding end of the machine; and thereupon the blanks are fed to the milling cutters; the grooves formed on the obverse surface; and thereupon automatically restacked in a duplicate removable magazine, which can then be removed and applied upside down to the feeding end alongside the magazine with the uncut blanks, and thus fed to the grooving cutters on the reverse side; and thereafter reassembled in a removable magazine, with the grooving completed on both sides.

The completely grooved blanks are then removed while assembled in the magazine for subsequent or coining operations.

A further important feature consists in the construction and arrangement whereby the blank, or blanks, are fed from the feeding end of the machine to and under the milling cutters

5 by first forcing and holding the blank, or blanks, firmly down upon the worktable, and thereupon clamping the blanks by a side-clamping operation; whereupon the hold-down is released and the continued movement of the worktable carries the blanks under the milling cutters for the grooving operation. This feature is most important, as it will be realized that the depths of the grooves cut depend upon the accuracy with which the blanks are positioned on the worktable which slides under the cutter.

These blanks are thin metal and must be accurately aligned, positioned, and firmly in contact with the top of the worktable to thus predetermine the position of the grooves and the depth of the same. The tolerance usually required for such operations, particularly the depth of the grooves which are in staggered relationship on the obverse and reverse sides, and overlapping each other in the interior of the blank, require a tolerance of from approximately two one-thousandths of an inch; while the side tolerance for alignment of the grooves must be within at least one one-thousandth of an inch.

20 The hold-down feature is further important just in advance of the side clamping because of the thinness and narrowness of the blank, and if the blank were not firmly seated on the worktable and held until the side clamps act, the blank might be sprung upwardly or otherwise distorted. Therefore, I arrange this hold-down operation under considerable pressure, which pressure is only released after the side clamps take hold; whereupon the hold-down pressure is removed, the blanks fed forwardly under the milling cutters, the grooving operation completed, the worktable drops from contact with the cutter, and the now-grooved blanks fed still further to be released by the side clamps and automatically assembled in a removable magazine. The magazines both for the feeding and removing are interchangeable, so that blanks stacked in a magazine and ready for removal are all ready to be fitted at the feeding end in reverse position for the grooving action on the other side, or removed for the subsequent notching operation.

Former machines left the blanks to tumble down in a box or receptacle and had to then be picked up and assembled into position by hand; but in my machine the blanks are always under positive control and are moved from one magazine into preassembled position in another for the grooving operation.

25 A further important feature is the construction wherein the length of the grooves is accurately predetermined. In carrying out this feature on a plurality of blanks, the worktable is mounted on a reciprocating slide, said worktable

and slide being moved to and fro under the milling cutters and from blank-feeding to blank-stacking position.

For this purpose I arrange the worktable to be raised and lowered relatively with the milling cutters, raising the table during the blank-feeding, clamping, and cutting operations; and thereupon quickly lowering the worktable with the blank clamped thereon to end the grooves and free the handle or coin portion of the key from contact with the cutters. This separation of the cutters and worktable is maintained when the worktable is moved back to starting position. This is accomplished by a cam underneath the worktable and operated as the worktable and slide are reciprocated, holding up the worktable during the grooving, and then dropping it during the completion of the feeding and during the return of the slide and worktable to blank-receiving position. Formerly the cutters were dragged back over the groove just cut, thus "chattering" and roughening the bottom of the groove, as well as dulling the cutters; while in my process and in my machine, the cutters and grooved blanks are vertically and positively separated enabling the ungrooved heads of the blanks to travel past the cutters.

It is also a novel feature of my present invention wherein the automatic filling or stacking of blanks into the magazine receiving them is effected by a vertical lifting operation, thus removing the blanks from the top of the worktable upwardly into the lower part of a magazine, or magazines. Thereby all the dust, millings, and the like, which formerly clung to the blanks after the milling operation, are more readily blown away and eliminated, and the speed and efficiency of handling is assured.

A further feature is the safety device which will automatically stop the machine if a blank is missing, or if a blank is jammed, or if particles lodge in the mechanism which would distort or deface the blanks or otherwise disalign or injure the grooving operation. For this purpose, I provide in connection with the hold-down a lever positioned to actuate a micro-switch which will disconnect the power and stop the machine in case of any difficulty, or in case the blanks run out in one stack. This is of great importance, as it enables an operator to handle a number of machines, and even if one runs out of blanks before being refilled, or if some difficulty arises as above noted, the machine will stop until corrective attention is received.

A still further very important feature consists in the arrangement and construction of the adjusting devices. It will be appreciated that the relative adjustment between the worktable, slide, and the milling cutters, both laterally, vertically, and longitudinally, is important.

These adjustments are made for an entire run of blanks; and particularly the adjustments of the feeding, hold-down, side clamps, and blank-ejecting devices to pre-stack the same in the magazine are necessarily made for great accuracy in the worktable and slide. It is also essential to provide a lateral adjustment of the entire slide and worktable relatively with the cutters. For this purpose I mount the reciprocating slide on a pivoted knee, having a pivotal support at one end with thrusting and tightening screws, or equivalent means, to adjust the entire knee and, hence, the slide and worktable laterally, as well as vertical adjusting means at the opposite end of the knee to raise or lower the

same; thus simultaneously positioning the worktable with its previously adjusted operating mechanism into desired relative cooperative position with the milling cutters.

These adjustments give lateral and vertical adjustments of the knee and, hence, of the slide and worktable carried by it, are easily accessible and, hence, readily made; and locking means to hold the same in adjusted position are quickly effected, while the adjustments on the worktable are not disturbed.

A further feature consists in the arrangement and facility for sharpening the milling cutters and for preserving these milling cutters against wear. It will be appreciated that the cutters rotate at high speed, and heretofore in the hand-operated or semi-automatic key-grooving machines, the cutters were required to be reground approximately after every one hundred gross grooving operations in order to continue accuracy in the depth and width of cut, and each cutter had to be removed in order to be resharpened.

In my present construction, wherein the worktable is dropped from the level of the groove-cutting operation and held in such dropped position out of contact with the cutters during the reciprocation of the slide and worktable, when returned to feeding position, all dragging on the cutters is thus prevented. In my present machine, the milling cutters will operate smoothly and accurately on upwards of one thousand gross without requiring regrinding and, hence, stopping of the machine for regrinding, and thus delaying production.

Also, I have constructed and arranged the cutters and assembled parts so that they may be reground while held in position on the spindle of the machine, thus still further saving delay in regrinding the cutters.

A special novel feature consists in my arrangement and operation of the means for removing the blank after the grooving operation and forcing it into a magazine, thus assembling the blanks and filling the magazine to its capacity during the continued and uninterrupted operation of the machine. For this purpose I provide a plurality of lifting pins sliding thru corresponding recesses in the worktable underneath the seat holding each blank. After the blank is fed thru the grooving cutters and is clear of the same, the blanks are then in position under vertically positioned magazines to receive the same; whereupon the side clamps are released and levers are operated to vertically lift the blank at a plurality of points into the magazine being filled, the blank moving upwardly past latches released for the purpose, and lifting the previously assembled blanks in the magazine, thus filling the same from the bottom upwardly.

As soon as the blank is thus engaged by the magazine, the lifting pins are retracted and the slide and worktable are moved quickly back to pick up a succeeding blank from the feeding magazines, and the operation is repeated.

While any suitable power-actuating means may be applied, I prefer to utilize compressed air under suitable pressure to actuate the various mechanisms which are supported on the knee, employing for this purpose a standard type of air piston. I find that a pressure of forty to fifty pounds is sufficient for quick actuation of the various moving parts necessary for the efficient speed of actuation of the machine mechanism. Thus I provide an air-controlled piston operating

in both directions for moving the slide carrying the worktable in its reciprocating movement, controlling said movement by contact of a bearing on the table against a rotating cam.

Similar air-actuated pistons are provided for forcing the hold-down in position and raising the same, for actuating the side clamps and releasing the same; for actuating the blank-lifting devices for filling a stack after grooving, and for air blasting to remove the millings, cuttings, and filings, dust, etc. from the worktable to insure a smooth resting or bedding of the blank so that the hold-down will force it firmly on its seat on the worktable.

For driving the cutters and cam shaft which are on fixed parts of the frame independent of the knee, I prefer to utilize an electric motor, one-half horsepower being sufficient.

The control of air supply to actuate the various air pistons both in forward and retracted positions is controlled by a rotating cam shaft, having a series of cams appropriately formed and operating the air supply in timed relation with the various mechanisms above briefly outlined, and as will be hereinafter more fully pointed out and claimed.

In addition to my novel machine and construction, I have devised and wish to claim herein the novel process of cutting and grooving blanks or equivalent operations in automatic combination with magazine-feeding and magazine-filling. As far as I am informed, the process of automatically taking one or more blanks successively from supplying magazines, moving them into operative relationship with cutting instrumentalities, and thereafter removing the blanks from cutting operation, and automatically filling a magazine by the orderly assembly in prearranged position of the blanks thus operated on, being at all times under control of positive machine actuations, is a novel and improved process, and I wish to claim the same herein.

Also the process of filling a magazine by vertical movement of successive novel blanks in prearranged position and relationship, thereby preparing the blanks in a magazine in assembled position for subsequent machine operations is a novel and improved process and I wish to claim the same herein.

Furthermore, positively separating the work and cutters by relatively vertical movement, such as dropping the worktable at a predetermined point in the cutting operation, is believed to be novel and is herein claimed.

Also the automatic feeding and grooving of a plurality of blanks, simultaneously cutting the grooves on the obverse side and the reverse side of an adjoining blank, and re-assembling same in a magazine, is a new and novel process, and I wish to claim the same herein.

Also automatically stopping the machine if the supply of blanks in a magazine is exhausted, or if a blank fails to feed, or is distorted, or is out of place on the worktable is new and novel.

While I have herein illustrated my improved process and machine construction for grooving key blanks, it will be appreciated that other and various types of work can be performed and that various novel features and constructions are broadly new and of wide application.

Further improvements, features, novel combinations, advantages, and constructions will be hereinafter more fully pointed out and claimed.

Fig. 10 is an enlarged detailed view of the automatic stopping device;

Fig. 11 is an enlarged fragmentary view of the lever-actuating stopping device;

Fig. 12 is an enlarged view partly in cross-section on the line 12—12 of Fig. 13, and

Fig. 13 is a side view of the bottom portion of the blank magazine key-holding devices.

Fig. 14 is a detailed view of the vertical adjusting device to raise and lower one end of the knee.

Figs. 15 and 16 are detailed, plan, and end views, respectively, of the box to which the feeding magazine is fitted.

As shown in the accompanying drawings, the present embodiment of my machine is constructed and arranged to operate upon a pair of blanks simultaneously, grooving the obverse of one blank while grooving the reverse of an adjacent blank. It is within the scope of the invention, however, to have a larger plurality of blanks simultaneously operated upon, if desired, by simply widening the worktable and blank-holding and grooving elements.

I prefer to arrange the machine as a complete self-contained unit having a suitable base on which are fixed several vertically extending standards to support the operating mechanism and, preferably, an electric motor in a convenient position to operate the cutters, and actuate a cam shaft which controls valves to a plurality of compressed air-actuated pistons. Other power means can be utilized, if desired, but I prefer to employ compressed air to move the worktable, the hold-down, the clamping and unclamping actions, and the blank-lifting and magazine filling operations. Compressed air is desirable, also, for clearing or blowing the millings after the cutting operations, thus cleaning the worktable, the side clamps, and the blanks for further movement or position for lifting the blanks into the receiving magazine. I find that a pressure of approximately forty pounds is sufficient for these various operations, both for blowing the millings, filings, etc. and for actuating the pistons to perform the detailed operations to be hereinafter described. If greater speed is desired, an air pressure of fifty to sixty pounds per square inch may be used.

Referring to the drawings, a suitable base of appropriate size supports a plurality of vertically extending standards by which the several machine elements are carried. As previously ex-

plained, an adjustable knee which carries the blank-feeding and operating devices is in the form of an inverted U and extends lengthwise of the machine.

Viewing Fig. 2, this knee 10 is supported at its left end on a pivot or trunnion 12, mounted in a pair of vertically extending supports 2-2 bolted to the base 1. Each support is shown as provided with a split circular head 5, having ears 6-6 which are clamped about the trunnion 12 by a headed bolt 6. The end portion of the knee, also viewing Fig. 2 at the left, is provided with a split extension to be clamped about the trunnion 12 between the supports 2-2, being similarly provided with extending ears 8-8 united by a headed bolt 9, with a head bearing on one ear and the shank threaded into a correspondingly tapped recess in the other.

To adjust the knee 10 laterally on the supporting trunnion 12, I provide thrusting and tightening screws, each having a turning head 16-16, with each shank 11 being threaded thru openings in the support 2-2 (see Fig. 8) and bearing against adjacent side portions 13 of the knee 10. Thus the entire knee and the portions of the machine carried thereby may be adjusted laterally on the trunnion 12 by loosening the headed bolt 9 and thereupon manipulating the adjusting screws 11 by rotating the head 16-16.

To raise or lower the opposite end of the knee from that engaging the pivotal trunnion 12, I provide a vertically adjusting screw 15 threaded thru the hub 17 formed on the cross-piece of the inverted U-shaped frame member 3 bolted to the base 1, see Fig. 2. The upper end of the adjusting screw 15 is concave, as shown at 18 (Fig. 2) to bear against a correspondingly convex face on the recessed block 19, which block is secured to a portion 20 of the knee, viz., at the free end of the knee opposite its pivotal bearing on the trunnion 12.

This block 19 is hollowed or recessed to receive the head 22 of a screw 21, which screw has its shank extending thru the adjusting screw 15. The head 22 is formed with a convex surface 25 to bear upon the bottom portion of the recessed block 19. The adjusting screw 15 is turned by a head 23, and a nut 24 tightened on the end of the T-headed screw 21 locks these parts in adjusted position while permitting the free end of the knee to be raised and lowered without binding. Thus, during the raising and lowering of this end of the knee to adjust the same for height, the nut 24 is backed off and the head 23 rotated, the curved bearing faces 13 and 25 serving to rock the knee on its pivot without binding the adjusting screw 15 or the T-head locking the screw 21.

To further brace, and particularly to lock the knee in any position to which it has been adjusted, I provide a pair of lugs 33-30 each on a depending portion or part of the inverted U of the knee, said lugs being between the pivotal trunnion 12 and the adjusting screw 15.

Each lug 30 has a convex face 31 (see Fig. 2) which will slidingly engage a concave surface on one of a pair of spaced heads 32, said heads being formed on a brace 35 extending from a bracket 36, which is attached by bolts 37 to the side of an upstanding frame member 40. A headed bolt 33 extends thru a slot in each head 32 of the brace and is tapped into its adjacent lug 30. Thus, to adjust the knee for height, the bolts 33-33 are loosened, the nut 24 is backed off, and the raising or lowering of the knee is effected by proper rotation of the vertically adjusting

screw 15. Thereupon the nut 24 is tightened and each bolt 33 is similarly tightened, locking the knee rigidly into the position to which it has been vertically adjusted.

The upper surface of the knee 10 is formed to receive the slide 40, the knee 10 being provided with a longitudinal groove in which a dovetailed rib 41 on the slide 40 will fit, a usual shim or gib 42 being fitted therein (see Fig. 7). This slide 40 carries the worktable 50, which worktable is pivoted to the receiving end of the slide, viz., at the right viewing Figs. 5 and 6, by a pivotal shaft 44, this shaft extending thru a pair of upstanding portions 45 on the slide 40, and said pivot also extending thru an adjacent portion of the worktable 50; whereby the worktable 50 will be carried back and forth on the slide 40, while permitting its opposite end face, at the left viewed in Figs. 5 and 6, to be raised and lowered relatively with the slide 40 during said reciprocations by the action of a cam, which will be explained later.

The slide 40 is reciprocated to and fro lengthwise on the knee 10 by a pinion 46 engaging a rack 47, see Figs. 5, 6, and 8, secured underneath the slide, said pinion being mounted on a shaft 48 and pinned thereto by a pin 55 passing thru the shaft, and a collar 49 being formed on one side of the pinion 46. This shaft 48 rotates in bearings 51 in the knee 10, and said shaft has one end 53 extended with an enlarged diameter, thus forming a shoulder 54, the shaft 48 thus being held against endwise movement between the collar 49 and the shoulder 54.

To rotate the shaft 48 and, hence, to reciprocate the slide 40 to and fro on the top of the knee 10, I provide a vertically extending rack rod 60 actuated by a piston within an air cylinder 61 attached to a frame 65 and bearings 66, carried by the knee 10, and said rack rod is in mesh with a pinion keyed on a portion 53 of the shaft 48, said pinion being indicated at 69, Fig. 4.

The lower portion of the rod 60 passes freely thru bearings 62 and 63 attached to a bracket 64, secured to the lower part of the knee 10, as best shown in Figs. 2 and 4. Compressed air, under control of a cam on a cam shaft, to be described, restricts the travel of the slide 40 and, hence, the rotation of the shaft 48 and gear 46, moving the slide and carrying the worktable to and fro. The reciprocating movement of the slide 40 is actuated by the air cylinder 61 against the restraining action of a cam 70 mounted in a pair of standards 71, see Fig. 2, and bearing against a roll 72 on a lever 73, pivoted at 74 adjacent the base 1, and having a top link 76 pivoted at 71 to the end of the lever 73, and having an adjustable connection 78 with a block 79 attached to the end of the slide 40.

Thus, the actuation of the piston and the air cylinder 61 is regulated and controlled by the restraining action of the cam 70, said cam being keyed to a cam shaft 80 and turning therewith. The extent of travel of the slide 40 and, hence, of the worktable 50 is sufficient to receive and pick the lowermost blank from a stack of blanks 81 in a vertically positioned and removable pair of magazines 82, 82 at the receiving end, or, the right viewed in Figs. 5 and 6; thereupon carrying said lowermost blank to the left, viewing said figures, under a hold-down, past the cutters; and into alignment with the receiving pair of magazines 84-84 (see Fig. 8).

Each of these two holders or magazines 84-84 are adapted to be removably fitted in a magazine

holder or shell, two of said shells 85—85 being side by side at the feeding end, and two holders 86—86, see Figs. 5 and 6, at the delivery end. These magazines may be slidingly fitted into the respective shells and readily removed and interchangeable. At the feeding end, viz., the right viewing Figs. 5 and 6, the lower portion of the shell 85 has a vertically extending plate 87 spaced slightly from the blank-supporting portion on the worktable to provide a gate 88, the plate 87 being of greater thickness than the upper part of the shell, so that the bottom rim of the magazine 82 will rest thereon, see Figs. 5 and 6. Thus, the stack of blanks 81 contained within the magazine 82, when the latter is slid and fitted into position on the feeding magazine shell 85, will rest on the plate 87 and permit the blanks therein to drop downwardly onto the worktable. All the blanks drop during the feeding, and later raise onto the top of the rail 92, being thus positioned when the table drops to prevent the next blank from moving out.

When the worktable is retracted to the extreme right or feeding position, the lowermost blank in the stack 81 will drop downwardly to be engaged by a blank-engaging rib 90 (Figs. 1, 5, and 6); and thereupon when the slide and worktable start the feeding travel to the left, viewing Figs. 5 and 6, the bottommost blank 91 from the stack will be fed thru the opening 88, Fig. 5. Secured on top of the worktable 50 are a pair of rails 92—92, 93—93, each having bevelled surfaces 94—94 which abut against the blank-engaging rib 90. These rails are spaced in line with each of the key blanks 91, which are fed from the bottom of the stack 81 in each of the shells 82 at the feeding end.

During the continued travel of the slide and worktable to the left, these bevelled faces 94 will pick up the remaining bottommost blank in the stack and raise the entire stack in its magazine 82, so that these blanks ride on top of the pair of rails 92 and 93 when the table drops. When the worktable is retracted to feeding position, the stack will be lowered along the bevelled faces 94 and at the extreme movement to the right, the rib 91 being moved to the right of each shell 85 and, thus, the rib 90 will pick up and engage the then bottommost blank, which will drop with the stack and be fed to the left in the next reciprocating movement of the slide and worktable. Each of the blanks 91 when dropped on the bed plate 95 will abut against side plates 89 fixed on the bed plate 95, and said plates 89 will be of slightly less thickness than that of the blanks 91. Corners 99—99 will hold the second key from feeding from the stack, see Fig. 9.

Each of the blanks 91 when fed clear of the feeding magazines 82 is engaged by a hold-down, and then by side clamps, being braced firmly on the bed-plate to receive the blank and thence the continued line of travel to the left, feeds the blank under the cutters for the length of groove for which the machine is set; whereupon the worktable is dropped downwardly and the continued feeding of the blanks past the cutters prevent the cutters from engaging the head of each blank, leaving the same free of grooves for subsequent ornamenting or coining operations.

This feeding movement to the left is continued until each blank now grooved is in alignment with its receiving magazine 84; whereupon the blank is lifted from its bed plate on the worktable and moved upwardly into the receiving magazine. Each blank, when taken from its feeding maga-

zine 82 is arranged to rest upon the bed plate 95 which is held by countersunk screws into a cross-piece 96 fitted into the top of the worktable 50. Bed plates of varying thicknesses can thus be readily and interchangeably fitted in the crosspiece 96.

In order to lift the blank 91 from the bed plate 95 on which it rests and to force same upwardly in the receiving magazine 84 after the grooving operation, I provide a plurality, for example, three lifting rods, in position to lift each blank from the plate 95 on which it rests. These rods 99 extend vertically thru reamed openings in the adjacent portion of the worktable 50, the crosspiece 96, and the bed plate 95 on which each blank rests during the grooving operation, and are attached at their lower ends to a block 100.

Each of these rods is threaded into the block, as shown in Figs. 5 and 6, and, as indicated in Fig. 5, is normally flush with the bottom of the bed plate, Fig. 6, illustrating the rods in raised position when lifting the blank 91 into the receiving magazine 84, where it is held by appropriate automatic latching devices to be described.

The block 100 is fitted within a longitudinal groove in each slot 40, each block 100 being itself slotted to receive a forked end 101 of a lever 102, which lever is mounted on a stud 103, said stud being attached to a lug 104 depending from the worktable 50. The forked end 101 of this lever engages a pin 105 extending across the slot in the block 100. The opposite end of the lever 106 extends outside the slot in the worktable and is pivotally attached at 107 to the lower end of a barrel 108, said barrel having an internal thread to engage the external thread 109 on the stem of a piston operating within the compressed air cylinder 110, said cylinder being mounted on a bracket 112 attached to the end of the worktable.

Normally the piston in the cylinder 110 is in raised position, thus holding the arm 106 upwardly and depressing the forked end of the arm 102 on this rocking lever so as to hold the rods 99 in lowered position relatively with the bed plate 95 and, preferably, flush therewith or slightly depressed below the surface.

Upon completing the line of travel of the worktable to the left and with the blanks in alignment with the receiving magazines 84, air is then supplied to the cylinder 110 and the piston moved downwardly, thus depressing the arm 106 of said lever, raising the arm 102 and moving the rods upwardly, lifting the grooved blank from the bed plate into the receiving magazine, as shown at Fig. 6. Each succeeding blank thus forces the entire stack of blanks 81 in the receiving magazine 84 upwardly by successive movements and rocking of this lever until the magazine is full. This rocking action and lifting of the blank is a speedy operation just at the time the worktable stops in its feeding movement to the left; whereupon the rods 99 are withdrawn and the slide and worktable retract their movement, traveling to the right to secure additional blanks.

In order to engage and hold these blanks 91 as they are lifted upwardly into position, I provide an automatic latching means, as best shown in Figs. 12 and 13. The shell 86 to hold the receiving magazine 84 is provided on its lowermost mouth or opening with a pair of sliding latches 115 adjacent the head of the blank 91 to be lifted therein, and a similar pair of latches

146 to engage and hold the shank part of the blank. The inner edges of each of these latches are bevelled, as shown at 117, so that as the blank is lifted upwardly on its ejecting pins 98, it will strike the bevelled faces 117 and force the latches 115 and 116 outwardly.

148 and 149 secured on the outside of the shell 86 engage, respectively, the heads of the sliding latches 115 and 116 and after the blank is forced upwardly beyond the bevelled faces in the bottom portion of each latch, the springs force the latches inwardly. The top of each latch is preferably formed with a latch 120 which will engage and hold the bottom portion of the blank 91 adjacent thereto after the blank has been forced upwardly into the stack 84. Adjusting rings 121 may be fitted between the heads of these sliding latches 115, if desired, to provide an adjustment for spacing the latch opening for blanks of different sizes.

During the time of travel of the worktable from blank-receiving to blank-ejecting position, each blank 91 is firmly pressed down upon its bed plate 95 after the blank has been moved thru the opening 88 and clear of its feeding magazine. For this purpose I provide a hold-down 130 vertically movable into and out of holding or clamping position by a cylinder 131. This hold-down 130 has a flat bottom surface 132 adapted to press a pair of adjacent blanks firmly and under considerable pressure upon the bed plate 95 supporting them. This hold-down is effected during a dwell in the travel of the worktable under the control of the cam 170, and during this hold-down action side clamping means to engage the sides of the blank are actuated. Thereupon the hold-down is released and the travel of the worktable to carry the blanks under the cutters is continued until the length of the grooving operation is completed at a predetermined point on the blank; whereupon the worktable is dropped to free the blank from further grooving, and the travel continued to aligning position with the receiving magazine, as previously explained.

This hold-down construction includes the block 130 formed with a semi-circular recess 133 in its upper surface, and a central circular portion 134 having a bored opening to receive a pin 135, securing the block 132 to the upper portion 134 also formed with a semi-circular bearing surface to fit the inner curve 133 on the hold-down block 130 itself. Thus the block 130 is adapted to rock on the pin 135, and as the bottom surface 132 spans a pair of blanks being fed, if one of the blanks is missing, or if the blanks are not firmly seated on the bed plate, the block 130 will rock and a lever 140 attached to the block will act to operate a microswitch 141 and instantly stop the mechanism, see Fig. 10, by cutting off the power to the motor.

The lever 140 is of considerable length and, therefore, will magnify any rocking action of the block 130. At the top of the lever 140 I provide a U-shaped member 142 secured to the end of the lever 140 by a headed bolt 143 tapped into a corresponding recess in the U-member 142. This member has a curved bearing surface 144 adapted to engage a concave recess in a plate 145 attached to a pivoted lever 146, which lever is mounted on a pivot 147 and is normally impelled by a spring 148 toward the bearing 144 on the U-shaped member. Thus, if the lower surface of the hold-down is not firmly and evenly seated, the top lever will move the bearing

144 out of its normal contact with the plate 145 against the tension of the spring 148 and will operate the micro-switch 141 by moving it inwardly against a projecting portion 149 on the end of the lever 146 opposite to its pivot. Thus the slightest rocking of the hold-down will actuate the micro-switch 141 and stop the machine.

In order to raise and lower the worktable 50 on its pivotal stud 44 connecting it with the slide 49 and during its line of travel both in feeding and retracting, I provide a cam 150 (see Fig. 7) formed with extending axles 151 and 152, and with a cam surface 153 adapted to bear against a hardened steel block 154 attached to the underneath portion of the worktable and substantially in position directly under the bed-plate holding the blanks to lift the worktable as it is retracted to the feeding end immediately after the key-holding seat has passed the position in vertical alignment with the cutters. The cam holds the worktable in raised position during the forward or grooving operation, moving to the left, and until the length of groove in the key-blanks has been cut; and thereupon the cam is rocked to quickly drop the worktable and free the head of each blank from action by the cutters.

The dropping of the worktable is cushioned by a pair of compression springs 155, 156 with the ends resting on the slide and worktable respectively, see Figs. 5 and 6, cushioning this lowering and dropping action. Thus the cam 150 is supported on a hardened steel block 158 fitted in a groove in the slide 49, the block 158 having a circular recess in its upper surface into which the semi-circular portion of the cam 150 is seated and adapted to rotate. A screw 159, see Fig. 7, holds the block 158 in position. On the axle portion 151 of the cam 150 is secured the latching and operating means for turning the cam in predetermined relation to the line of travel to lift the worktable during the retraction to feeding position and holding it up during the grooving operation and to lower it immediately thereafter.

For this purpose I provide a bearing block 160 to take the thrust of cocking the lever 165, said block fitted around the portion 151 with its inner surface in contact with the side walls of the worktable 50, said axle portion as well as the opposite portion 152 extending thru enlarged recesses 161, 161 so as to be free of contact therewith, the central cam portion being held in longitudinal position by washers 162 at each end, said washers spanning the openings 161, as clearly shown in Fig. 7. This cam 150 is constructed and arranged to be rocked by the traveling action of the slide and worktable and spring 184.

For this purpose a cocking lever 165 is secured to the portion 151 of the cam 150 by a set screw 166, the lower portion of the lever 165 having an offset extension 167 which is in line to strike against a plate 169 when the slide and worktable are being retracted to the feeding position, to the right viewing Figs. 2, 5, and 6. This partially rotates the cam 150 and raises the worktable, the lever 165 being held in this position by a trigger 170, with its lower arm 175, mounted on a pivot 173 on the worktable, said trigger having a notch 171 in the arm 170 to engage a corresponding notch in the hub portion of the cocking lever 165 surrounding the portion 151 on the cam. Thus the trigger 170—175 holds the cam in raised position and holds the lever 165 during the further retraction of the slide beyond this point and until, on the feeding movement of the slide to the left, the lower portion 175 of

the trigger strikes against pin 179 projecting from a depending arm 178.

This occurs when the lever 165 has passed the top of the plate 169 and also when the grooving cutters have completed their grooving action on the blanks. The parts 178 and 180 combine to cause the part 178 to trip when they engage the adjustable trip block 176 secured in desired and adjusted position in the side of the knee, see Fig. 2.

Thus, during the feeding action of the worktable, moving to the left and carrying the blanks to be grooved by the cutters, the worktable will be held in raised position as it carries the blanks under the cutters and until the depending portion 180 strikes the trip block 176; whereupon the trigger 170—175 is depressed, releasing the latch 171 from holding the cam in raised position and permitting the table to drop, at this point the arm 167 being beyond the block 168. The booster spring 177 and the coiled spring 184 accelerate the rotation of the cam 150 and, thus, further insures the dropping of the worktable at the proper moment during the travel of the same to free the head end of the blanks from the action of the grooving cutters.

On the return to feeding action, the block 168 acts to lift the lever 165, turn the cam and raise the table which is thus held in uppermost position until released on the feeding line of travel, as above noted.

Both the blocks 168 and 176 are adjustably secured to the sides of the knee 10 by headed bolts passing thru slotted openings in the block and being threaded into correspondingly tapped recesses in the adjacent part of the knee, thus permitting adjustment of these tripping blocks 168 and 176 to act in timed relation, thereby providing for different lengths of grooves.

The lever 165 with its depending offset portion 167 being moved past the plate 169, is free to be depressed when the trigger 170—175 is released from its engagement by disengaging the notch 171. The cam 150 is turned in reverse direction to drop the worktable by the combined action of a spring 184 attached at 185 to a stud on the worktable and at the other end to a depending lug 186, having a hub 187 encircling the portion 152 and secured thereto by a set screw 188.

In addition to this spring 184, provided on the back of the machine (see Fig. 7) is a "booster" spring in a cylinder 176 attached to the side of the worktable adjacent the latch 165, as shown in Fig. 2, and at an angle so that a spring-pressed plunger 177 will engage the latch 165; and when this latch is released by the trigger 170—175 and has passed the length of the plate 169, as explained, the internal spring surrounding the plunger 191, in combination with the tension of the spring 184, will move the cam 150 downwardly and thus drop the table during its continued travel to the left.

The trigger 170—175 is moved upwardly by a spring 174 to engage the notched end 171 and hold the same when the lever 165 is raised by striking the plate 169 on the reverse movement of the slide to feeding position. A bevelled surface 168 on the end of the plate 169 constitutes a cocking block against which the lower extension 167 strikes, and thereby raises the lever and turns the cam, thus lifting the table, as previously explained, during travel of the worktable to feeding position.

The action of the hold-down 130 on the blanks has been above briefly explained, and while the

blanks are thus firmly pressed against the bed-plate 95 on which they rest, and before the hold-down is released by the upward movement of the piston in the air cylinder 131, I provide side clamping devices to engage and hold each blank against the fixed ribs or plates 89 after the hold-down is raised and during the continuous travel of the blanks under the cutters and until in position for being lifted into the receiving magazines.

Thus the bed plate 95 has attached thereto fixed inner ribs or plates 89 against which sliding outer plates 194 press each blank. I provide a pair of clamping arms 190, 190 positioned horizontally adjacent the top of the worktable and pivoted therein at 191, said arms being extended (see Fig. 9) at 192, and each having a threaded screw 193 carrying the adjacent sliding plate 194 to engage the side of the adjacent blank when the arms are moved on the pivots into blank-clamping position. These sliding plates are of less thickness than the blanks; see Fig. 7.

This movement is effected by a pair of connecting links 195—195 pivoted at the opposite end of the arms, as shown at 196, 196 (Fig. 9), said links being pivoted at 197 to a horizontally movable block 198 adjustably connected by a threaded portion 199 of the piston of the air cylinder 200. Thus when air is admitted to the cylinder 200 to move the rod 199 to the right, viewing Figs. 1 and 9, the clamping arms are rocked on their pivots 191 to engage the blanks 91, which have been firmly pressed downwardly into the recesses in the bed-plate to receive same by the hold-down 130.

This clamping action is held by the air cylinder 200 until the completion of the travel of the worktable; whereupon the valve controlling said air cylinder is reversed and the piston moved in the opposite direction to release the blanks while the lifting pins are actuated to lift each blank up into the receiving magazine 84 at the moment that the travel of the slide and worktable to the left stops and before the return travel to the right commences.

The cylinder 200 is secured on a bracket 201 (see Fig. 2) carried by the worktable. I provide an adjustable stop to limit the clamping closing action of the lever bearing and members 193 on the blanks so as to prevent too much clamping power to be exerted on these blanks, as they are narrow, and might spring upwardly where an excessive amount of side-clamping power is exerted thereon.

For this purpose I provide a threaded rod 205 fitted into a correspondingly tapped recess in an extension 206 on the end of the worktable 50, providing thereon a thumb nut 207 to rotate this threaded screw and thus give the adjustment desired. A locking nut 208 holds the adjusting screw 205 in position. I also utilize the extension 206 in which to seat one end of the springs 155 (see Fig. 5) to cushion the worktable 50 which drops by its own weight when released by the lowering action of the cam 150. These springs 155 are also, preferably, encircling rods 210, which rods are guides for the springs and each is secured in the top of the extension 206 on the worktable, and have the lowermost end 212 lifted from contact with the slide 40 during the raising action of the worktable.

While the magazines 82 and 84 will be held by sliding the same into the magazine shells 85 and 86, respectively, I prefer to clamp these in position by a wing nut 215 binding a clamp 216, thus

firmly locking the shell and magazine together, a wing nut 215 turning the screw 211, having its opposite end tapped into the adjacent portion of the shell 85, see Figs. 5 and 6.

Also, in addition to the latches 415 and 416, as previously described and best shown in Fig. 12, to hold the blanks in raised position, I may and preferably do have a pair of pivoted arms 220, 220 (Fig. 5) having fingers at the lower portion of each arm 222 to guide the opposite ends of each blank as it is lifted into the receiving magazine 84, each finger having a bevelled face 221 grooved to fit the end of the key and to guide the blank laterally and longitudinally, said guiding grooves being indicated in dotted lines, Fig. 6, at 316 and 317, so that the raising of each blank will spread the arms 220 apart as the blank is lifted above the same, similar to the manner in which it spreads the spring plungers 415 and 416. These clamping arms 220 are pivoted on right-angled extensions 223 of each arm to pivot pins 224 in a receiving shell 86, the extensions 223 being united at their inner ends by a forked member 225 on one arm, and an engaging ball-like round end 226 on the other arm. Thus the two pivoted arms 220 are spread apart and spring backwardly into position underneath the blank as it is moved up, thus positively guiding the same in alignment with the receiving magazine 84.

These pivoted arms 220 are forked at the top and bottom portions and are solid intermediate the same to receive a tension spring and adjustable stop nut, as shown in Fig. 6, these details being omitted from Figs. 2 and 5. While these arms 220 would work by gravity as the blanks are pushed up by the same, I prefer to utilize a spring and adjustable stop which permits higher speed in the lifting of the blanks 91 into the receiving magazine, and which can be on one or both arms 220.

For this purpose, the central part of the arm 220 is perforated, as shown in dotted lines at 310, Fig. 6, said perforation being of greater diameter than the stem of a bolt 311 which passes therethru, thus allowing for swinging action of the arms 220. The bolt 311 has its inner end threaded and tapped into correspondingly threaded recesses into the shell 86, and the head of the bolt 312 is enlarged to bear against a conical spring 314 encircling the stem 311 of the bolt and being seated between the head and the lever 220.

In order to afford a stop for the swinging action of the levers 220, I arrange an adjustable stop 315, being threaded thru the solid part of the arm 220 adjacent the bolt 311 and having its inner end abutting against the side of the shell 86. Thus rotation of the stop member 315 and adjustment of the tension of the spring 314 gives a predetermined and limited quick-acting swinging movement of the arms 220.

A lock nut 316 may be provided to hold the stop member 315 in adjusted position. One such spring and stop nut will insure the uniform action of both arms 220, although it is, of course, feasible to put a corresponding spring and stop member on the opposite arm 220. The lower portion 222 of each of these arms is forked, providing a spread to cooperate with a pair of blanks being fed into the receiving end, as shown in Fig. 8, and each end is formed to constitute a guiding element for the blanks as they are pushed upwardly by the pin 99 into the receiving magazine receptacle.

During this transfer, the blanks are lifted and

"floating" on top of the pins and, hence, the guiding action of the swinging arms 220 is important to insure the blanks being lifted into position, where they are caught by the spring clamps, as shown in Figs. 12 and 13.

For this purpose, the right-hand ends of the forked arms 222 are grooved or concave to correspond roughly with the curve of the head of the blank, as indicated in dotted lines at 316, Fig. 6; while the opposite or left-hand members, viewing Fig. 6 are notched to correspond with the opposite end of the blank, as indicated in dotted lines at 317, thus affording an aligning and guiding action during the blank-lifting operation.

It is important to keep a considerable number, such as ten or twelve blanks, in the box 87 cooperating with the receiving magazine 84.

These constitute a weight so that when a blank 91 is lifted on the pins 99 into alignment with the stack of blanks 81, the weight of the accumulated blanks in the box serve to steady the same and prevent the blank being lifted from getting disaligned or crosswise. As the pins 99 are snapped up quickly because of the speed of operation, such a blank, without the steady action of the weight of the superimposed ten or twelve blanks therein, would tend to snap up and possibly be wedged in disaligned position.

Referring to Figs. 15 and 16, I have illustrated in detail the box 87 in alignment with the feeding magazine 82, wherein I fit a filler piece 320 appropriate in width and depth to approximately fit the length and width of the shank portion of the particular blanks being operated on. This filler piece is readily removable for different sizes of blanks and made of wood, and is preferably of the same height as the depth of the box 87. The underneath portion of the box 87 is grooved, as shown at 321 and 322, the latter grooves also extending thru the wooden filler piece 320 to permit the rails 82 to pass thru and underneath the box as the worktable is moved to the left, carrying a blank being operated upon, the rails lifting the remaining blanks 81 in the feeding stack 82, as previously explained, to keep the bottom blank from feeding forwardly until the next retraction of the worktable to feeding position.

The milling cutters to form the grooves are single or arranged in pairs, where two grooves in the blank are to be formed, and are mounted on a shaft 230, each pair of cutters being designated, respectively, as 231 and 232, see Figs. 7 and 9. The pair of cutters 231 are positioned to form the grooves on the obverse side and the cutters 232 form the grooves on the reverse side when the blanks are put thru the second time. This shaft 230 is mounted in bearings 233 supported on top of the frame member 39 and, hence, are rigidly positioned with the shaft 230 extending over the movable slide and worktable to rotate the cutter shaft 230.

Any suitable source of power can be utilized but, preferably, I provide an electric motor 236 in order to make the apparatus an entirely self-contained unit. This motor is mounted at one side of the machine, see Figs. 1, 3, and 4, being held in a support or strap 237 mounted on a supporting member 238, having its lower portion formed with hubs 239 to fit over and be carried by a stud 240 fitted into the frame 39. The motor 236 is provided with a reduction gear suitably enclosed, as indicated in 241, and the shaft extending from the reduction gear driving a

pulley 242, which pulley has one or more belts 243 uniting the pulley 244 secured to the cutter shaft 230. The arrangement of mounting the motor 236 on the brace 238, positioning same at an angle relatively with the supporting stud 240, permits me to utilize this arrangement to tighten and loosen the driving belts 243, the weight of the motor constituting the tensioning and tightening means for said belts.

Thus the cutter shaft 230 is driven directly and continuously by the motor 236 and the cutters are in constant rotation until and unless the machine is stopped by the action of the safety lever 140 on the hold-down 130, as previously explained or by disconnecting the power.

The cutter shaft 230 is extended to carry a pulley 250 around which a belt 251 is led to a pulley 252 (see Figs. 1, 3, and 4) mounted on a stud 253, extending from the frame 39, said pulley 252 being formed on a hub and carrying a gear 255, which is in mesh with an idler 256 turning a pinion 257 rotating the cam shaft 80, thru engagement with the gear 258, said shaft being mounted in bearings 260, 260, see Fig. 3, supported by the frame.

To this cam shaft is keyed the restraining cam 10 regulating the travel of the worktable under the actuation of the air cylinder 61 and rack and gear pinions, as already explained, and also carries cams 262, 263, 264, and 265 which actuate the air valves for the various air cylinders in timed relation through the engagement, respectively, of levers 272, 273, 274 and 275. The cam and levers 262 and 272 regulate the air control to the various air cylinders. Thus the cam 262 operates the lever 272 to actuate the air valve 276 to the hold-down cylinder 131 through a pair of conduits 277. The cam 263 and lever 272 actuate the air valve 280 through the conduits 281 to the cylinder 61; the cam 264 and lever 274 actuate the air valve 284 and through the conduits 285 to the cylinder 110 which rocks the lever 106 and raises the lifting pins.

The cam 265 and connecting lever 275 actuate the air valve 288 thru conduits 289 to operate the air blast to clear out the millings and clean the bed plate to receive the next set of blanks.

The various controlling cams and operating levers are all standard and of usual construction, each lever having an appropriate bearing, roll, or piece to engage the cam. The quick-acting cam which operates the air control for the cylinder 110, for example, serves to instantaneously rock the lever to eject the completed blanks and move them into the receiving magazines, being in the form of a quick-acting wiper type cam and follower, for example.

The air valves are operated to successively admit air under pressure from forty to fifty-five pounds, depending on the speed of operation desired, admitting the air supply in the air cylinders on one side of the internal piston; and thereupon the valve shuts this supply off and opens the supply for the other side of the piston, simultaneously opening the first conduit to permit the pressure to exit therefrom. These air cylinders are of standard construction and operate on each side of an internal piston in the usual manner of a steam engine.

A clutch 300 is controlled by an overload micro-switch motor cut-out 301 energized thru wires 302 to a source of power which acts to disconnect the power to the motor 236 in case of an overload on the clutch 300. The receiving magazines 82—82 are fitted in their respective shells at the

feeding end of the machine and clamped by turning the wing nuts 215; whereupon the slide 40, if not in the extreme right or feeding position, is moved to the same by the operation of the air cylinder 61, turning the gear 46 and, hence, moving the slide 40.

With the slide 40 and worktable 50 in the extreme right hand end of their travel, the lowermost blank 91 of the stack 81 in each of the magazines at the feeding end of the machine will drop down onto the bed plate 95, which is at starting position underneath the same, the back end of each blank being engaged by the strip 90 and thereupon fed thru the opening 88, and the worktable 80 being in raised position at this time. As the worktable moves to the left, the bevelled faces 94 on the rails 92 lift the remaining blank in the stack 81 so that they will not be displaced nor jam in the opening 88, and the table is moved under the impulse of the air cylinder 61 but in timed relation because of the restraining action of the cam 70.

Thus, when the worktable and the blanks 91 are fed clear of the opening 88, the travel of the worktable will cease momentarily while the hold-down is actuated by the cylinder 131. Thereupon, the side clamps are actuated by the cylinder 200, moving the clamping arms laterally and the plates 194 carried by each move under the hold-down and clamp the blanks against the inner rigid ribs 89. These clamping plates 194 are pivoted to the arms at 193 so that they provide a self-seating action against the key blanks. Thereupon, the hold-down is raised and the table continues its travel, viz. passing under the cutters 231 and 232. If one blank is displaced or missing, or in distorted shape, or not properly seated, the hold-down will rock the lever 140 and stop the machine by the action of the micro-switch 141, as illustrated in detail in Fig. 10.

Continued travel of the worktable completes the grooving action; whereupon the trigger 170 releases the cam 150 by rocking the lever 165 under the influence of the spring 84 and the booster spring in the cylinder spring 176, thus lowering the worktable, dropping it on its pivot 44 secured to the slide 40, and continuing the travel until the blanks are under the receiving magazines 84. Thereupon, the side clamps are released by the retraction of the piston and air cylinder 200, and the air cylinder 110 acts to raise the pins under the grooved blank and into the receiving cylinders; whereupon the pins are dropped by the reverse movement of the piston in the cylinder 110 and the travel of the worktable is retracted by the reverse action of the piston in the cylinder 61, turning the gear 46 in the opposite direction for this purpose.

During the first line of travel, the worktable 60 is still in lowered or depressed position but when past the line of cutters, the extension 167 on the arm 165 raises the cam 150 and, hence, the table, the table being held in raised position by the latching of the trigger 170 into the notch 171 until released. This operation is continued until all the blanks are transferred from the feeding magazines 82 to the receiving magazines 84.

Thereupon the receiving magazines can be removed and the magazine holding the blanks with the groove on one side only is inverted and positioned in the feeding magazine shell for grooving on the reverse side, while a new magazine is fitted for the first grooving operation on the obverse side. The machine operation is thus entirely automatic and because of the quantity

of blanks in each magazine, one operator can attend to a considerable number, and the capacity and speed of output is thus greatly increased.

When it is desirable or necessary to adjust the worktable, either when blanks of different thicknesses are to be operated upon or where the grooves to be formed by the cutters 231 and 232 are to be changed with relation to the length of the blanks, the adjustments of the knee 10 can be quickly and easily effected, each automatically and simultaneously produces the adjustment desired in the worktable and, hence, both laterally and vertically relatively with the cutters.

For this purpose, the bolts 33 on each side of the knee 10 are loosened and the nut 24 backed off slightly from the vertical adjusting screw 15. Thereupon, the tightening screws 16 are manipulated to adjust the knee laterally on the trunnion 12, and the vertical adjustment is effected by the manipulation of the head 23 on the nut 15. The grooved surface 31, 18, and 25 permit this adjustment with full bearing contact on the abutting parts and without binding.

Thereupon the bolts 33 and nut 24 are tightened, thus locking the knee in the newly adjusted position. These adjustments on the knee and the slide and worktable carried by it are in accessible positions, as above explained, and hence are more likely to be made by the operator and without loss of time. No additional adjustments are necessary to be made to the machine when shifting blanks either for thickness, length, or width, the side clamping plates 194 attached to the clamping arms being automatically adjusted to the blanks as they effect a self-seating upon the same against the fixed inner ribs 89; a slight adjustment of the stop 205 being made to limit the power exerted by the side clamps on the blanks.

It will thus be seen that I have provided a completely automatic machine and instrumentalities capable of high-speed of output, universal adjustability for blanks of varying sizes and thickness, and with a varying actuating mechanism effected in timed relation, together with an efficient and instantly acting stop mechanism should a blank be missing, distorted, or not properly seated on the bed blade prior to the operation of the cutters. Also, by having the worktable drop and thus vertically separate the cutters and the blanks after the length of groove desired has been formed in each blank, the grooved blanks are carried beyond the cutters and are positively stacked in the receiving magazine in assembled alignment for removal and for subsequent operations.

By having the cutters instantly free of contact with the blanks, the grooves formed thereby are more smooth and more accurate than any prior machines where the blanks had to be dragged backwardly after the grooving action and the cutters would chatter over the grooves, which latter action also tended to dull the cutters, necessitating constant sharpening.

In my present apparatus I am enabled to affix a sharpening element and resharpen the cutters when needed when still on their shaft 230, thus further effecting a great saving of time and permitting the machine to be in more constant operation.

Also, my improvement in this art, wherein a plurality of articles from one magazine are fed thru operating instrumentalities and then automatically stacked into another magazine, prefer-

ably interchangeable with the first, is believed to be new and is claimed broadly herein.

Furthermore, the method of operating on a plurality of blanks or partly finished articles wherein they are fed to a worktable, hold-down pressure applied thereon, and thereupon side-clamping devices actuated which hold the articles until carried by the operating instrumentalities, either with or without a dropping of the worktable at a predetermined point, is believed to be new and is claimed herein. As far as I am informed, my method of vertically lifting articles after a machine operation thereon, re-stacking the articles into a receiving magazine or the like, is novel and I wish to claim the same herein broadly.

I claim:

1. A machine of the kind described for grooving key blanks for a portion of their length, while automatically transferring the blanks from predetermined assembled position in a delivery magazine to a similar predetermined position in a duplicate receiving magazine, comprising a reciprocating worktable movable from adjacent the delivery magazine past grooving cutters to the receiving magazine including, means to position and to hold a blank on said movable table from one magazine to the other, and means including a cam actuated by the travel of the worktable and automatically actuated in timed relation with the reciprocating movement of the worktable to raise the worktable during the cutting action and to drop said worktable and separate the blanks from the grooving cutters at a predetermined point in the grooving operation, to limit the length of the grooves being cut.
2. A machine of the kind described for grooving flat key blanks for a portion of their length, while automatically transferring the blanks from a delivery magazine to a duplicate receiving magazine, comprising a reciprocating worktable movable from adjacent the delivery magazine past grooving cutters to the receiving magazine, means to position and to hold a blank on said movable table from one magazine to the other, and means automatically actuated when the grooved blank and worktable are adjacent the receiving magazine to release the blank from the table and to move each blank upwardly into said magazine in predetermined stacked relation.
3. A machine of the kind described for grooving a plurality of key blanks simultaneously, comprising a plurality of portable delivery magazines and a plurality of duplicate portable receiving magazines, a movable worktable for receiving blanks from each of said delivery magazines and transferring the same to each of the corresponding receiving magazines in predetermined stacked relation, milling cutters to operate on the plurality of blanks being so transferred between the respective delivery and receiving magazines, and means automatically actuated to vertically move a completed blank from the worktable to its respective receiving magazine.

4. A machine of the kind described, comprising milling cutters, a worktable movable under said milling cutters, a slide on which said worktable is moved, said slide being mounted on a pivoted knee, means for laterally adjusting said knee on its pivot, and means for vertically adjusting the opposite end of the knee.

5. In a machine of the kind described, milling cutters, a movable worktable in association with said milling cutters, means to hold and carry

a blank on said worktable into cutting relation with said milling cutters, a receiving magazine, and means thereafter to separate the blank from the table by automatically actuated lifting devices, raising the blank from the table and positively forcing said blank into the receiving magazine, in combination with latching means to hold a blank in said magazine.

6. In a machine of the kind described, milling cutters, a movable worktable in association with said milling cutters, means to hold and carry a blank on said worktable into cutting relation with said milling cutters, a receiving magazine, and means thereafter to separate the blank from the table by automatically-actuated lifting devices, comprising a plurality of vertically movable pins slidably extending thru the worktable, and means to raise said pins to lift a blank into said receiving magazine. 10

7. In a machine of the kind described, milling cutters, a movable worktable in association with said milling cutters, means to hold and carry a blank on said worktable into cutting relation with said milling cutters, a receiving magazine, and means thereafter to separate the 20

blank from the table by automatically-actuated lifting devices, comprising a plurality of vertically movable pins slidably extending thru the worktable, and means to raise said pins to lift a blank into said receiving magazine, and means to lower said pins after the blank has been lifted into the receiving magazine.

ARTHUR L. CURRIER.
